CHASER-HOLDER FOR THREAD-CUTTING TOOLS

Albert F. Breitenstein, New Haven, Conn., assignor to The Geometric Tool Company, New Haven, Conn., a corporation of Connecticut

Application June 7, 1937, Serial No. 146,765

14 Claims. (Cl. 10—104)

This invention relates to improvement in chaser-holders for mounting thread-cutting chasers in thread-cutting tools, such, for instance, as in self-opening die-heads.

5 One of the objects of the present invention is to provide a superior chaser-holder by means of which the thread-cutting capacity of a thread-cutting tool may be conveniently altered.

10 A further object is to provide chaser-holding means whereby a self-opening die-head or the like may be utilized for cutting a wide range of thread diameters without requiring the replacement of one chaser-holder by another.

15 Another object is to provide a superior chaser-holder of the character referred to whereby various thread diameters may be cut by employing in a given self-opening die-head or the like chasers having substantially the same length.

20 A still further object is to provide a superior chaser-holder by means of which it will be necessary to stock only chaser-blanks of substantially the same dimensions in order to cut a range of thread diameters with a given thread-cutting tool.

25 Still another object of the present invention is to provide superior chaser-holding means whereby, in order to effect a change-over from cutting right-hand threads to cutting left-hand threads, or vice versa, it will not be necessary to replace 30 an entire chaser-holder.

With the above and other objects in view, as will appear to those skilled in the art from the present disclosure, this invention includes all features in the said disclosure which are novel over 35 the prior art.

In the accompanying drawings, in which certain modes of carrying out the present invention are shown for illustrative purposes:

Fig. 1 is a view mainly in side elevation and 40 partly in section of a self-opening die-head equipped with chaser-holders embodying the present invention;

Fig. 2 is a view thereof in front elevation;

Fig. 3 is a fragmentary sectional view taken on 45 the line 3—3 of Fig. 2;

Fig. 4 is a similar view taken on the line 4—4 of Fig. 2;

Fig. 5 is a sectional view taken on the line 5—5 of Fig. 3;

50 Fig. 6 is a front-face view of one of the chaser-holders, detached, and showing a chaser mounted therein;

Fig. 7 is a perspective view of the base-member 55 of the chaser-holder, looking mainly toward the forward face thereof;

Fig. 8 is a similar view of the chaser-mounting member of the holder, looking mainly toward the rear face thereof;

Fig. 9 is a perspective view of the locating-stud; and

Fig. 10 is a similar view of the chaser.

For the purpose of illustrating the present invention, there is shown in the accompanying drawings a self-opening die-head having the forward face of its body 20 provided with four (more 10 or less) T-shaped guide-grooves 21, each of which is adapted to receive and guide for reciprocation the T-shaped guide-tang 22 of a reciprocating base-member, generally designated by the numeral 23, and including, in addition to the tang 22, just referred to, a forward sector-shaped plate-portion 24.

Inasmuch as each of the four body-members 23 corresponds to each other, a description of one thereof, together with its associated parts, 20 will serve for all.

The outer end of each of the body-members 23 is formed with an inclined cam-surface 25 which is adapted to be engaged by a similarly-inclined internal cam-surface 26 formed within the forward end of a ring-like operating-sleeve 27. The said operating-sleeve encircles the body 20 of the die-head and is adapted to slide axially upon the same to control the radial movement of the chaser-holder. When the operating-sleeve 27 is 30 moved forwardly it acts to force the various body-members 23 bodily inwardly and to maintain the same in such position. When the said chaser-operating sleeve 27 is moved rearwardly, each of the body-members 23 of the chaser-holder and the parts carried thereby will be permitted to move radially outward into a retired position in a manner hereinafter described.

Each body-member 23 is urged outwardly by a pair of cup-shaped plungers 28—28 (Figs. 1, 3 40 and 4), each of which is adapted to reciprocate in a suitable substantially-radial bore 29 formed in the body 20 of the die-head structure directly back of the guide-groove 21 in the latter. Each plunger 28 is urged outwardly by a helical spring 45 30 and engages with a thrust-pin 31, two of which latter project rearwardly from each of the body-members 23.

The detailed character of the various die-heads in which the chaser-holders of the present invention may be mounted does not require detail description herein beyond that already given other than to say that in the self-opening die-head shown the operating-sleeve 27 may be axially adjusted upon the body 20 to effect the 50 55

slight advancement or retirement of the base-members 23 and the parts carried thereby, by means of an adjusting-nut 32 mounted upon the threaded portion 33 of the shank 34 of the die-head structure.

On each of the respective opposite sides of the tang 22 the rear face 35 of the plate-portion 24 of the base-member 23 is adapted to ride upon the front face of the body 20 of the die-head structure as is particularly well shown in Figs. 1 and 4. Each base-member 23 is formed on its forward face with a substantially-radial guide-groove 36 which is adapted to receive a substantially-radial guide-rib 37 projecting from the rear face of a sector-shaped chaser-mounting member 38 which in the manner as will hereinafter appear is clamped against the front face of the said plate-portion 24 of the base-member 23 with capacity for substantially-radial adjustment with respect thereto.

The outer portion of the rear face of the guide-rib 37 just above referred to is formed with a plurality of transverse locating-teeth 39 which are adapted to selectively interfit with similar but forwardly-extending locating-teeth 40 formed upon the forward face of the head-portion 41 of a locating-stud 42. The locating-stud 42 just referred to is firmly seated in a forwardly-opening counter-board recess 43 formed in the base-member 23 centrally of the groove 36 therein as particularly well shown in Figs. 4 and 7. The said locating-stud is retained in place by an anchoring-pin 44 extending therethrough and through the adjacent portion of the tang 22 of the base-member 23.

The base-member 23 on each of the respective opposite sides of the radial groove 36 therein is formed with a threaded bore 45 receiving the threaded shank of a clamping-screw generally designated by the reference character 46 and having its outer end located in a counter-bored slot 47 in the chaser-mounting member 38 so that its polygonally-socketed head-portion lies substantially flush with the forward face of the said member 38. The two clamping-screws 46—46 as thus arranged serve to firmly attach the chaser-mounting member 38 to the base-member 23 so that the guide-rib 37 is maintained in the guide-groove 36 to thus restrain the member 38 from twisting with respect to the member 23 in a plane parallel with the coacting faces of the two said members. The clamping-screws 46 also serve to maintain the locating-teeth 39 of the chaser-mounting member 38 in interfitting engagement with the locating-teeth 40 of the locating-stud 42 which latter in a functional sense may be considered integral with the base-member 23. By means of the interengaging locating-teeth 39 and 40 the chaser-mounting member 38 is prevented from being displaced radially outwardly with respect to the base-member 23.

Formed in the inner contracted edge of the chaser-mounting member 38 is a chaser-receiving notch 48 which extends from front to rear through the said member and is bounded by opposed side walls 49—49 and by an outer end wall 50. Installed in the chaser-receiving notch 48 of the chaser-mounting member 38 is a substantially-rectangular chaser 51 having thread-cutting teeth 52 at its inner end and transversely pierced by a passage 53 which is flared at one end to provide a conical cam-surface 54. Substantially in line with the passage 53 through the chaser 51 the chaser-mounting member 38 is formed with a threaded bore 55 into which is

threaded the threaded shank 56 of a chaser-seating screw generally designated by the reference character 57 and including a polygonally-socketed head-portion 58 joined to the threaded shank 56 by a conical cam-surface 59. The head 5 of the screw 57 is located in a bore 55a in the wall of the member 38 opposite the threaded bore 55 and the cam-surface 59 of the said screw is adapted to engage with the conical cam-surface 54 in the chaser 51 to force the said chaser outwardly firmly into engagement with the end wall 50 of the notch 48 and into firm engagement with the opposite wall 49 of the said member (Fig. 5).

The outer end of the chaser 51 opposite the thread-cutting teeth 52 is formed with a transverse notch 60 into which extends the flattened end of a stabilizing-stud 61 rigidly positioned in a socket 62 opening through the end wall 50 of the notch 48 in the chaser-mounting member 38. The projecting flattened end of the stabilizing-stud 61 by projecting into the notch 60 in the chaser 51 serves to prevent the outer end of the chaser from being cocked forwardly under the stress developed when the thread-cutting teeth 52 of the chaser are in action.

In all of the figures preceding Fig. 6 the chaser-mounting member 38 is shown as adjusted to the limit of its outward movement with respect to the base-member 23 so as to cut the maximum diameter of thread with a given size of chaser which diameter in the setting shown is 1". Should it be desired to cut a thread of $\frac{3}{4}$ " diameter each of the chaser-mounting members 38 may be moved inwardly by first loosening the clamping-bolts 46 sufficiently to permit the said mounting-members to be moved forwardly with respect to their complementary base-member 23 a distance sufficient to disengage the locating-teeth 39 of the members 38 from the locating-teeth 40 of the members 23 whereupon the said members 38 may be moved inwardly the equivalent of the distance between an adjacent pair of the locating-teeth referred to which in the construction shown are spaced at eighth-inch intervals. If desired the chaser-mounting members 38 may be moved radially inwardly relative to their respective base-members 23 a distance corresponding to the spacing of the locating-teeth to thus provide in the particular structure chosen for illustration for the cutting of threads of $\frac{1}{2}$ " diameter as shown in Fig. 6.

When the chaser-mounting members 38 have been moved the desired distance (within the range provided by the slots 47) the locating-teeth 39 and 40 are reengaged and the clamping-screws 46 tightened to re-lock the members 38 and 23 together into a unit. A suitable chaser of substantially the same over-all dimensions as the chaser 51 may now be installed in the chaser-receiving notches 48 in place of the said chasers 51, if desired.

As thus constructed and arranged, the two-part chaser-holders provide for increments of adjustment in a radial direction corresponding to the spacing of locating-teeth 39 and 40 thereby making it possible to employ chasers of substantially the same length for cutting threads of various standard diameters without requiring the replacement of the chaser-holders by other chaser-holders. Furthermore by providing chaser-holders of the character shown and described the manufacturer may stock chasers or chaser-blanks of the same dimensions with the assurance that such chasers may be interchangeably used with a die-head equipped with holders of the 75

present invention for cutting various thread diameters within the range of the particular die-head. In the instance shown and described the chaser-holder provides for adjustments in increments of $\frac{1}{8}$ " though greater or lesser increments may be provided for but in the event that it is desired to cut a thread diameter intermediate the increments referred to the chaser-blanks may be ground back an appropriate amount. It 10 may be here noted that in the usual manner of self-opening die-heads, the adjusting-nut 32 provides for adjusting the chaser-holders as a whole within a limited range.

In addition to other advantages to chaser-holders as above described, it may here be noted that in the event that it is desired to make a change-over from a set-up for cutting right-hand threads to a set-up for cutting left-hand threads or vice versa, it is necessary only to replace the 20 chaser-mounting members 38 and substitute in conjunction with the remaining base-members 23 a similar chaser-mounting member having its chaser-seating screw 57 extending therethrough in the opposite direction from that of the members 38.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

35 I claim:

1. A composite chaser-holder for thread-cutting tools, comprising: a base-member having means thereon for interfitting with a die-head; a complemental chaser-carrying member carried 40 by the said base-member with capacity for bodily rectilinear adjustment with respect thereto, the division between the two said members being in a plane substantially parallel with the front face of the die-head structure; and locking-means extending between the two said members and binding the same into a unitary structure.

2. A composite chaser-holder for thread-cutting tools, comprising: a base-member having means thereon for interfitting with a die-head; a complemental chaser-carrying member having an inwardly-opening chaser-receiving socket and carried by the said base-member with capacity for bodily rectilinear adjustment with respect thereto, the division between the two said members being in a plane substantially parallel with the front face of the die-head structure; and locking-means extending between the two said members and binding the same into a unitary structure.

60 3. A composite chaser-holder for thread-cutting tools, comprising: a base-member having means thereon for interfitting with a die-head; a complemental chaser-carrying member having an inwardly-opening chaser-receiving notch and being carried by the said base-member with capacity for bodily rectilinear adjustment with respect thereto, the division between the two said members being in a plane substantially parallel with the front face of the die-head structure; and locking-means extending between the said members and binding the same into a unitary structure.

70 4. A composite chaser-holder for thread-cutting tools, comprising: a base-member having means thereon for interfitting with a die-head; a

complemental chaser-carrying member having an inwardly-opening chaser-receiving notch extending thereacross from its forward to its rear face, the said chaser-carrying member being carried by the said base-member with capacity for bodily adjustment with respect thereto and having the rear terminus of its chaser-receiving notch intersecting the forward face of the said base-member; and locking-means extending between the two said members and binding the same into a unitary structure.

5 5. A composite chaser-holder for thread-cutting tools, comprising: a base-member; a complemental chaser-carrying member carried by the said base-member with capacity for bodily rectilinear adjustment with respect thereto; and locking-means extending between the two said members and binding the same into a unitary structure; the said base-member having a rearwardly-projecting tang for interfitting with a die-head and also having a locating-shoulder extending transversely with respect to the said tang for engagement with a locating-shoulder on the said chaser-carrying member, and the said chaser-carrying member having a chaser-receiving seat and a locating-shoulder engageable with the locating-shoulder of the said base-member.

15 6. A composite chaser-holder for thread-cutting tools, comprising: a base-member; a complemental chaser-carrying member carried by the said base-member with capacity for bodily rectilinear adjustment with respect thereto; and locking-means extending between the two said members and binding the same into a unitary structure; the said base-member having a rearwardly-projecting tang for interfitting with a die-head and also having a plurality of locating-teeth extending transversely with respect to the said tang for engagement with a plurality of locating-teeth on the said chaser-carrying member, and the 20 said chaser-carrying member having a chaser-receiving seat and the plurality of locating-teeth engageable with the locating-teeth of the said base-member.

25 7. A composite chaser-holder for thread-cutting tools, comprising: a base-member having a rearwardly-projecting tang for interfitting with a die-head and also having a locating-shoulder extending transversely with respect to the said tang for engagement with a locating-shoulder 30 on the said chaser-carrying member; a complemental chaser-carrying member carried by the said base-member with capacity for bodily rectilinear adjustment with respect thereto and having a chaser-receiving seat and a locating-shoulder engageable with the locating-shoulder of the said base-member; and locking-means extending between the two said members and binding the same into a unitary structure; the division 35 between the two said members being in a plane substantially parallel with the front face of the die-head structure.

45 8. A composite chaser-holder for thread-cutting tools, comprising: a base-member having a rearwardly-projecting tang for interfitting with a die-head and also having a plurality of locating-teeth extending transversely with respect to the said tang for engagement with a plurality of locating-teeth on the said chaser-carrying member; a complemental chaser-carrying member 40 carried by the said base-member with capacity for bodily rectilinear adjustment with respect thereto and having a chaser-receiving seat and a plurality of locating-teeth engageable with the locating-teeth of the said base-member; and locking-means extending between the two said members and binding the same into a unitary structure; the division 45 between the two said members being in a plane substantially parallel with the front face of the die-head structure.

- locking-means extending between the two said members and binding the same into a unitary structure; the division between the two said members being in a plane substantially parallel with the front face of the die-head structure.
5. A composite chaser-holder for thread-cutting tools, comprising: a base-member having a fixed rearwardly-projecting tang rigid therewith for interfitting with a die-head and having a forward sector-shaped stabilizing portion extending laterally on each of the respective opposite sides of the said tang and engageable with the forward face of a die-head; a complemental chaser-carrying member also of sector shape and carried by the said base-member with capacity for bodily rectilinear adjustment with respect thereto; and locking-means extending between the two said sector-shaped members on each of the respective opposite sides of the tang of the said base-member and binding the said members into a unitary structure.
9. A composite chaser-holder for thread-cutting tools, comprising: a base-member having a fixed rearwardly-projecting tang rigid therewith for interfitting with a die-head and having a forward sector-shaped stabilizing portion extending laterally on each of the respective opposite sides of the said tang and engageable with the forward face of a die-head; a complemental chaser-carrying member also of sector shape and carried by the said base-member with capacity for bodily rectilinear adjustment with respect thereto; and locking-means extending between the two said sector-shaped members on each of the respective opposite sides of the tang of the said base-member and binding the said members into a unitary structure.
10. A composite chaser-holder for thread-cutting tools, comprising: a base-member having a fixed rearwardly-projecting tang rigid therewith for interfitting with a die-head and having a forward sector-shaped stabilizing portion extending laterally on each of the respective opposite sides of the said tang and engageable with the forward face of a die-head; a complemental chaser-carrying member carried by the said base-member with capacity for adjustment with respect thereto, the division between the two said members being in a plane substantially parallel with the front face of the die-head structure; and locking-means extending between the two said members on each of the respective opposite sides of the tang of the said base-member and binding the said members into a unitary structure.
11. A composite chaser-holder for thread-cutting tools, comprising: a base-member having a fixed rearwardly-projecting tang rigid therewith for interfitting with a die-head and having a forward sector-shaped portion extending laterally on each of the respective opposite sides of the said tang and engageable with the forward face of a die-head; a complemental chaser-carrying member also of sector shape and carried by the said base-member with capacity for adjustment with respect thereto, the division between the two said sector-shaped members being in a plane substantially parallel with the front face of the die-head structure; and locking-means extending between the two said members on each of the respective opposite sides of the tang of the said base-member and binding the said members into a unitary structure.
12. A composite chaser-holder for thread-cutting tools, comprising: a base-member having a forwardly-projecting tang for interfitting with a die-head and also having a locating-shoulder extending transversely with respect to said tang for engagement with a locating-shoulder on the said chaser-carrying member; a complemental chaser-carrying member carried by the said base-member with capacity for bodily rectilinear adjustment with respect thereto and having a chaser-receiving seat and a locating-shoulder engageable with the locating-shoulder of the said base-member; and a pair of locking-screws extending between the two said members and binding the same into a unitary structure and respectively located on the opposite sides of the said tang.
13. A composite chaser-holder for thread-cutting tools, comprising: a base-member having a rearwardly-projecting tang for interfitting with a die-head and having a forward sector-shaped portion extending laterally on each of the respective opposite sides of the said tang and engageable with the forward face of a die-head; a complemental chaser-carrying member also of sector shape and carried by the said base-member with capacity for adjustment with respect thereto, the division between the two said sector-shaped members being in a plane substantially parallel with the front face of the die-head structure; and a pair of locking-screws respectively located on the opposite sides of the tang of the said base-member and extending between the two said members to bind the same into a unitary structure.
14. A composite chaser-holder for thread-cutting tools, comprising: a base-member having a rearwardly-projecting tang for interfitting with a die-head and having a forward sector-shaped portion extending laterally on each of the respective opposite sides of the said tang and formed in its forward face with a substantially radial locating-groove; a locating-stud having locating-teeth thereon and mounted in the said base-member in position to have its locating-teeth projecting into the locating-groove thereof; a complemental chaser-carrying member also of sector shape and carried by the said base-member with capacity for adjustment with respect thereto and formed on its inner face with a guide-rib formed with a plurality of locating-teeth and projecting into the locating-groove of the said base-member into engagement with the locating-teeth on the locating-stud therein; and a pair of locking-screws one of which extends between the said sector-shaped members on each of the respective opposite sides of the said guide-groove and the said guide-rib thereof.

ALBERT F. BREITENSTEIN.
